UNITED STATES PATENT OFFICE.

ADAM SCHOTT, OF OAKLAND, CALIFORNIA.

CLOTHES-POUNDER.

1,098,978.

Specification of Letters Patent. Patented June 2, 1914.

Application filed December 16, 1912. Serial No. 737,064.

To all whom it may concern:

Be it known that I, ADAM SCHOTT, a citizen of the United States, residing at Oakland, in the county of Alameda and State of California, have invented certain new and useful Improvements in Clothes-Pounders; and I do declare the following to be a full, clear, and exact description of the invention, such as will enable others skilled in the art 10 to which it appertains to make and use the same.

This invention relates to washing machines of the pounder or plunger type; and the object of the same is to produce a very 15 simple clothes pounder made by preference entirely of sheet metal excepting the wooden handle, and by means of which the finest and most fragile fabric can be thoroughly cleansed in a few minutes' time without rubbing and without the use of a wash board. This and other objects are carried out by 20 constructing the machine in the manner hereinafter more fully described and claimed, and as shown in the drawings wherein—

25 Figure 1 is a side elevation of this device complete. Fig. 2 is an enlarged vertical section through the head or lower end of the pounder constituting the washing machine, and Figs. 3 and 4 are cross sections on the 30 lines 3—3 and 4—4 of Fig. 2 respectively.

Referring now more particularly to the attached drawings, the casing or body 1 of this machine is an upright cylindrical member or shell from whose upper end rises a 35 dome- or cone-shaped top 2 pierced at one side with an opening 3 closed by a screw cap 4 through which soap may be fed into the machine when the cap is removed. The body is by preference cylindrical, and disposed concentrically within it is the inner shell 5 which is also by preference a cylindrical member shorter and of less diameter than the outer cylinders. The upper end of the inner shell is closed by a horizontal partition 6 which is extended out to the angle 7 between the body 1 and top 2 and perforated as at 8 above the annular space 9 between the outer and inner members. Secured as by soldering upon the partition 6 at its 40 center 10 is an upright tube 11 which passes through the apex of the cone 2 and is secured as by soldering at the point 12, and extends a little above said apex in a ferrule 13; and the wooden handle 14 is inserted 45 through this ferrule and down the tube until it rests upon the partition 6, being se-

cured therein by any suitable means such as a split pin 14'. Around said tube is an annular space of triangular cross section into which access is had through the opening 3 when the cap 4 is removed, and this space communicates through the perforations 8 with the annular space 9 between the two cylinders, and also communicates through a number of rather large openings 15 with the 50 interior space 16 within the inner shell 5.

The lower end of the inner shell is cut off on a line 17 somewhat above the lower end 18 of the outer shell or body 1, and across said lower end of the inner shell are perforated straps 19 whose ends are extended outward and downward as at 20 and connected with the lower end or mouth of the outer shell or body 1, there being several of these straps suitably secured where they cross each other and where they cross the lower ends of the two shells and their function obviously being to give rigidity to the shells and to hold them properly spaced so as to maintain the parts in proper relative position. 55

The operation of this machine is as follows: The clothing to be washed is placed in a tub and covered with water, and a little soap, preferably in the form of lump, is passed through the opening 3 and the screw 60 cap put tightly in place. The handle 14 being now inserted into the socket and fastened therein as by means of the split pin 14', the operator grasps this handle and puts the head of this device into the tub, and 65 then by reciprocating the handle vertically the clothing is washed by the pounding action of the plunger as it is brought down upon it. In the descent of the device the large open mouth 17 of the inner shell admits a considerable volume of water which, 70 drives the air above it upward through the openings 15, then radially outward, and thence downward through the perforations 8 into the annular space 9 and out the lower 75 end 18 of the outer shell so that it is ejected downward onto the clothes by the very act of pounding them with this machine. This air is saturated with water, and in its passage through the course outlined, the water 80 takes up the soap which is in lumps and agitates it within the conical top 2, and therefore soapy spray is driven downward through the perforations 8 and the space 9 and onto the clothes. On a reverse movement due to the upward motion of the 85 device, the volume of water within the inte-

rior 16 of the inner shell moves downward and therefore creates a partial vacuum within the top 2, with the result that the air within the annular space 9 is drawn 5 upward more rapidly than the device is ascending and a certain amount of suction is created above the clothing. The result will be that the soapy water is sprayed onto the clothes at the very time that they are 10 pounded by the machine, and is again sucked upward through and from the clothes at the very time that pressure thereon is removed by the elevation of the device; and I have found by experiment that 15 the most delicate and fragile fabrics can be washed by this machine in a short period of time and with a few vertical reciprocations of the instrument.

As above suggested, the parts are by preference entirely of sheet metal or other metal suitably treated to prevent rusting, and the connections are made by soldering or brazing excepting that the cap 4 should screw onto a nipple surrounding the opening 3. 20 I do not wish to limit myself to the exact means suggested for fastening the handle in place, and in fact such handle might be a permanent part of the device instead of being of wood and removable. 25

What is claimed as new is:

The herein described clothes pounder comprising an outer cylindrical body, a conical top closing the upper end thereof, a horizontal partition across the body on a line with its juncture with said top, the 30 partition having perforations around its edge and larger openings near its center, an upright handle-tube fixedly mounted on said top, an inner shell concentric with and shorter than the cylindrical body and secured at its upper end to said partition inside the perforations through the latter so as to leave an annular space between the body and shell which is of less volume than the inner shell and crossing straps of perforated metal forming the bottom of the 35 body and located a suitable distance from the lower edge thereof, said straps being uniformly separated, whereby a suction chamber is formed below the bottom thus 40 formed.

In testimony whereof I have hereunto set my hand in presence of two subscribing witnesses.

ADAM SCHOTT.
